DENTAL CABINET OR THE LIKE

John J. Valeska, Rochester, N.Y., assignor to Sybron Corporation, Rochester, N.Y.

Filed Oct. 21, 1970, Ser. No. 55,594

Term of patent 14 years

Int. Cl. D24—03; D6—01

U.S. Cl. D24—1

FIG. 1

FIG. 1 is a front top view of the perspective dental cabinet, showing my new design;

FIG. 2 is a top plan view thereof; and

FIG. 3 is a front elevation view thereof.

I claim:

The ornamental design for a dental cabinet or the like, substantially as shown.
